CLAIM

The ornamental design for an armboard clutch assembly, as shown and described.

DESCRIPTION

FIG. 1 is a bottom-front-right perspective view of an armboard clutch assembly according to the claimed design. FIG. 2 is a bottom-rear-left perspective view of the armboard clutch assembly.

FIG. 3 is a bottom-rear-right perspective view of the armboard clutch assembly.

FIG. 4 is a bottom-front-left perspective view of the armboard clutch assembly.

FIG. 5 is a bottom view of the armboard clutch assembly.

FIG. 6 is a top view of the armboard clutch assembly.

FIG. 7 is a front view of the armboard clutch assembly.

FIG. 8 is a rear view of the armboard clutch assembly.

FIG. 9 is a left side view of the armboard clutch assembly.

FIG. 10 is a right side view of the armboard clutch assembly; and,

FIG. 11 is a front-left perspective view of the armboard clutch assembly with an armboard of a patient support table shown in environment.

The dashed lines in FIGS. 1-10 depict portions of the armboard clutch assembly that form no part of the claimed design. The additional dashed lines in FIG. 11 depict environmental subject matter and form no part of the claimed design.

The dash-dot broken lines in the drawings define the bounds of the claimed design and form no part thereof.
